The ornamental design for a watch, as shown and described.

DESCRIPTION

FIG. 1 is a top plan view of a watch embodying my invention;

FIG. 2 is a bottom plan view thereof;

FIG. 3 is a side elevational view thereof;

FIG. 4 is an opposite side elevational view thereof;

FIG. 5 is an end view thereof; and,

FIG. 6 is an opposite end view thereof.

The broken-line showing of hands in FIG. 1 is environmental only and forms no part of the claimed design.
